GILL DRAWING FRAME

Ralph C. Berker, Hoxsie, R. I.

Application October 25, 1951, Serial No. 253,041

10 Claims. (Cl. 19—129)

1

The invention relates to improvements in gill drawing frames, particularly in the means for applying pressure on the top roller of the drawing rollers of a gill drawing frame.

The usual set of drawing rollers of a gill drawing frame comprise lower steel rollers and a top pressure roller which may be made of a rubber or rubber-like synthetic type of material for providing a yielding surface contact with the slivers being drafted. The pressure on the top roller is usually provided by means of an individually adjustable compression spring at each end of the top roller to apply an adjustable pressure thereon. It is necessary when the machine is to remain at rest for any considerable length of time, such as over night or a week-end, to release the pressure of the springs on the top roller because such pressure on the top roller with the machine at rest will tend to produce an undesirable permanent flat in the surface of the top roller at the point of contact therewith with the bottom roller or rollers. This requires individual readjustment the next time the rollers are to be used.

A general object of the invention is to provide a means for applying a resilient force on the top roller of the drafting set of rollers of a gill frame, which force may be controlled from a single point to quickly release the force and return it without disturbing the adjustment of the spring pressure which supplies the force.

Another object of the invention is to provide a means for applying a resilient force on the top roller of the drafting rollers of a gill frame at opposite ends of the top roller in which the force may be adjusted from a single point.

Another object of the invention is to provide a means for applying a resilient force on the top roller of the drafting rollers of a gill frame at opposite ends of the top roller in which the said force may be applied and released by manual operation of a single handle without disturbing the adjustment of the spring pressure.

A more specific object of the invention is to provide a movable abutment for engaging the compression springs of the top roller of the draft rollers of a gill frame, which said abutment may be moved from a single point for adjusting the pressure of such springs and which may be moved for releasing the pressure of such springs without disturbing the adjustment of such springs.

Another object of the invention is to provide a movable abutment for the compression springs of the top roller of a gill drawing frame to engage therein, which said abutment will be supported merely by its physical contact with the

said springs and which may be moved at a single point thereon in a manner whereby the force applied thereto will be equalized on the springs compressed thereby.

With these and other objects in view, the invention consists of certain novel features of construction as will be more fully described and particularly pointed out in the appended claims.

In the accompanying drawings:

10 Figure 1 is a side elevational view of a fragmentary portion of a gill drawing frame illustrating the mountings of the front drawing rollers and the position relative to the gill head.

15 Figure 2 is a front elevational view of the frame shown in Figure 1 looking in the direction of the arrows on line 2—2 of Figure 1 with certain portions shown in Figure 1 omitted.

Figure 3 is a section view taken substantially along line 3—3 of Figure 2.

20 Figure 4 is a perspective view of an abutment for one end of the top roller springs to engage.

25 Referring to the drawings for a more detailed description of the invention, 10 designates a gill drawing frame illustrating the side frames 11 between which is mounted the gill head 12 of any conventional manufacture, having usual combs for processing wool slivers or other materials in a usual manner, the wool slivers being drawn from the combs by means of a front drafting roll set 13 designated generally. Each lower roller 14—15 of the said set 13 is provided with extensions or trunnions, 16—16, 17—17 respectively which are journaled in bearings 18 which are adjustably secured to the said side frames 11. These lower 30 rollers are driven in a usual manner by a means not shown.

35 The upper or top roller 19 of the set 13 is reduced at its ends to provide trunnions 20, and its body 21 is covered with a rubber or rubber-like synthetic material so as to provide a yielding surface for contacting and providing a bite on the sliver passed between the said top and bottom rollers. The top roller is mounted in a supporting frame 22 comprising two arms 23 secured to each other at their upper ends by a channel bar 24 extending transversely between the said arms and secured in place by bolts 25. The other or lower ends of the arms 23 are each provided with an opening 26 extending therethrough which openings are in line with each other. A pivot pin 27 projects inwardly from each bearing 18 into said openings 26 for pivotably mounting said arms 23 for swingably moving said support 22 from a substantially horizontal position to a generally vertical position as seen in Figure 1.

The top roller 19 is positioned to engage both the said lower rollers 14-15 to provide a bite therebetween and is rotatably held in position on said frame by bearings 28 which are slidably secured on the arms 23 by means of cap bolts 29 which extend through slots 30 in the arms 23 and threadably engage the said bearings 28. The bearings are positioned above the trunnions 23 of the top roller and the lower edges of the bearings are each provided with a semi-circular bearing recess 31, in which said trunnion 20 rests. Each bearing 28 is also provided with a spring positioning projection 32 which is of relatively short length. A compression spring 33 is positioned to rest against the upper side of each bearing 28 and encircles the said projection 32 which holds the said spring in proper relation with the said bearing 28.

An abutment for the other or upper ends of the springs 33 is provided in the present embodiment of the invention by a bar 34 having a central recess 35 and with enlarged circular heads 36 at the ends thereof. Each head is the same and has a recess 37 (see Fig. 1) in the lower side thereof which also opens outwardly axially in line with said bar as at 38. The bar is positioned to extend transversely between the arms 23, and the springs 33 are received in said recesses 37 to abut against the bottom wall 39 of the recesses.

The channel bar 24 is provided with a central bearing opening 40 in line with the said recess 35 and surrounded by a boss 41. A sleeve 42, the lower end of which is internally threaded, is rotatably and slidably received in said opening 40. The upper portion of said sleeve 42 extends above the boss 41 and has a collar 43 secured thereto as by means of a screw 44. A rod 45 extends radially from said collar 43 and provides a handle for turning said sleeve in said opening 40. The lower end of the sleeve 42 extends a substantial distance beyond the lower side of the bar 24 and has secured on the end portion thereof a circular member having a cam 46 on its upper face, the cam 47 of which faces inwardly or toward said lower side of the bar 24. A second circular member 48 having a similar cam on its lower surface 49 matching the said cam surface 47 surrounds the sleeve 42 and is provided with opposite arms 50 which engage the under side of the bar 24 and are attached thereto by means of bolts 51. A threaded member 52 having a knurled head 53 threadingly extends through said sleeve 42 so that its rounded end will be received in said recess 35 to engage the bottom wall 35' thereof, said recess 35 being of much larger diameter than the diameter of the member 52.

It will now be apparent that the pressure of the springs on the heads 36 will move the bar 34 upwardly and through the member 52 will urge said cams 46-48 into engagement with each other. Turning the member 52 in one direction or other will adjust the force on said bar 34 substantially midway thereof by adjustment of the tension of the springs 33, the force of the member 52 being equalized on the springs 33.

It will also be apparent that turning this sleeve 42 in one direction will position the high point of the cams in engagement with each other and position the bar 34 at its lower position which will hold the springs 33 under compression. Turning the sleeve 42 in the opposite direction or further turning the same in the same direction will cause the high points of the cams to ride beyond each other and each will engage the lower point of the other as seen in Figure 2 whereby the 75 roller.

bar 34 under the urge of the springs 33 will be raised.

In operation the sleeve 42 is turned to position the high points of the cams in engagement with each other at which position the bar 34 as previously stated will be at the lower position of movement as urged by the said cams 46-48. The member 52 may now be turned in the proper direction to adjust the pressure of the springs 33 to that required on the roller 19. Since the force of the member 52 is applied at the mid point of the member 34, the ends or heads 36 of said bar 34 will be equally moved against such springs engaged thereby, and thus an equal adjustment of spring pressure is had at the ends of the roller 19 by the application of a force at a single point. When the gill frame or machine is to remain idle for such a period as over night or week-ends and like periods of inactivity, the operator relieves the pressure of the springs 33 on the roller by a simple turning of the handle 45 to turn the sleeve to position the high point of one cam in engagement with the low point of the opposite cam, thereby freeing said bar to be raised to permit the expansion of said springs to zero pressure, this being accomplished, of course, without disturbing the pre-set adjustment of the position of the member 34 relative to the sleeve 42. At this position of member 34 the top roller 19 will rest only by its weight on the lower rollers 14-15, and this is insufficient to deform the surface of the top roller in a manner for a permanent set at the points of contact with the lower rollers 14-15. When the machine is again to be placed in operation, the sleeve is turned to position the high points of the cams in engagement with each other as shown in Figure 3 to move the springs 33 into compression at the preset adjustment of tension thereof.

When it becomes necessary to remove the top roller 19 from the machine to provide repairs or substitute another roller, it is merely necessary to permit the springs 33 to expand to zero pressure by means of turning the sleeve 42 to permit raising of member 34. At this position of spring expansion the springs are easily removed by pulling the same out through the opening 38 of the recesses 37. Then the bolts 29 may be loosened to disengage the same from the bearings 28, and the latter may be lifted from the trunnions 23. The roller 19 is now free of the bearings and may be easily pulled from between the frame 22, thus saving considerable labor over that of prior construction wherein the removal of the top roller 19 involved considerable dismantling of top roller supporting structure.

I claim:

1. In a gill drawing frame having a top pressure roller, a compression spring at each end of the top pressure roller for applying an adjustable pressure on said top roller, a movable abutment for one end of said springs, said abutment being under pressure of said springs tending to move said abutment in a direction to permit expansion of said springs, means for applying a force on said abutment at a mid point thereon for adjustably moving said abutment to adjust the pressure of said springs on said top roller, and second means operable for releasing said abutment to the action of the spring pressure thereon for releasing the pressure of said springs on said top roller and for moving said abutment against the pressure of said springs to return said springs in the adjusted compression relation thereof with said top roller.

2. In a gill drawing frame having a top pressure roller, a compression spring at each end of the top pressure roller for applying an adjustable pressure on said top roller, a movable abutment for one end of said springs, said abutment being under pressure of said springs tending to move said abutment in a direction to permit expansion of said springs, means for applying a force on said abutment at a mid point thereon for adjustably moving said abutment to adjust the pressure of said springs on said top roller, and cam means operable for releasing said abutment from the action of the spring pressure thereon for releasing the pressure of said springs on said top roller and for moving said abutment against the pressure of said springs to return said springs to the adjusted compression relation thereof with said top roller.

3. In a gill drawing frame having a top pressure roller, a compression spring at each end of the top pressure roller for applying an adjustable pressure on said top roller, a movable abutment extending between and engaging said springs, said abutment being under pressure of said springs tending to move said abutment in a direction to permit expansion of said springs, means for applying a force on said abutment at a mid point thereon for adjustably moving said abutment to adjust the pressure of said springs on said top roller, and second means operable for releasing said abutment from the action of said spring pressure thereon for releasing the pressure of said springs on said top roller and for moving said abutment in a direction against the pressure of said springs to return said springs to the adjusted compression relation thereof with said top roller.

4. In a gill drawing frame having a top pressure roller, a compression spring at each end of the top pressure roller for applying an adjustable pressure on said top roller, means for adjusting the pressure of said springs and for quickly releasing the pressure of said springs on said top roller comprising a raising and lowering member engaging said springs, said member being under pressure of said springs tending to move said member in a direction to permit expansion of said springs, means engaging said member at a central location thereof to adjust the pressure of said springs and further means operable for lowering said member against the pressure of said springs to place the same under compression and operable for permitting said member to be raised by expansion of said springs.

5. In a gill drawing frame having a top pressure roller, a compression spring at each end of the top pressure roller for applying an adjustable pressure on said top roller, a support, an abutment movable relative to said support and extending between and providing an abutment for one end of said springs, said abutment being under pressure of said springs tending to move said abutment in a direction to permit expansion of said springs, a rotatable member carried by said support and mounted for turning movement thereof and for axial movement thereof, a threaded member threadedly extending through said rotatable member into engagement with said abutment at a location thereon midway thereof for adjustably moving said abutment axially of said springs for adjusting the pressure thereof, and interengaging means carried by said support and rotatable member for moving said rotatable member axially thereof upon rotatably turning said rotatable member.

6. In a gill drawing frame having a top pressure roller, a compression spring at each end of the top pressure roller for applying an adjustable pressure on said top roller, a support, an abutment movable relative to said support and extending between and providing an abutment for one end of said springs, said abutment being under pressure of said springs tending to move said abutment in a direction to permit expansion of said springs, a rotatable member carried by said support and mounted for turning movement thereof and for axial movement thereof, a threaded member threadedly extending through said rotatable member into engagement with said abutment at a location thereon midway thereof for adjustably moving said abutment axially of said springs for adjusting the pressure thereof, and interengaging cam means carried by said support and rotatable member for moving said rotatable member axially thereof upon rotatably turning said rotatable member.

7. In a gill drawing frame having a top pressure roller, a compression spring at each end of the top pressure roller for applying an adjustable pressure on said top roller, a support, an abutment movable relative to said support and extending between and providing an abutment for one end of said springs, said abutment being under pressure of said springs tending to move said abutment in a direction to permit expansion of said springs, a sleeve carried by said support and mounted thereon for turning and axial movement thereof, a threaded member threadedly extending through said sleeve into engagement with said abutment at a location thereon midway thereof for adjustably moving said abutment axially of said springs for adjusting the pressure thereof, and interengaging means carried by said support and sleeve for moving said sleeve axially thereof upon rotatably turning said sleeve.

8. In a gill drawing frame having a top pressure roller, a compression spring at each end of the top pressure roller for applying an adjustable pressure on said top roller, a support, an abutment movable relative to said support and extending between and providing an abutment for one end of said springs, said abutment being under pressure of said springs tending to move said abutment in a direction to permit expansion of said springs, a sleeve mounted on said support for rotatable movement and for axial movement thereof, a threaded member threadedly extending through said sleeve into engagement with said abutment at a location thereon midway thereof for adjustably moving said abutment axially of said springs for adjusting the pressure thereof on said top roller, a cam fixed to said support, a cam carried by said sleeve extending into engagement with said first cam, said cams being related such as to move said sleeve axially to lower or permit raising of said abutment upon turning of said sleeve.

9. In a gill drawing frame having a top pressure roller, a compression spring at each end of the top pressure roller for applying an adjustable pressure on said top roller, a support, an abutment movable relative to said support and extending between and providing an abutment for one end of said springs, said abutment being under pressure of said springs tending to move said abutment in a direction to permit expansion of said springs, a sleeve mounted on said support for rotatable and axial movement thereof, a threaded member threadedly extending through said sleeve into engagement with said

abutment at a location thereon midway thereof for adjustably moving said abutment axially of said springs for adjusting the pressure thereof on said top roller, a cam fixed to said support and encircling said sleeve, a cam encircling said sleeve and secured thereto for moving therewith and extending into engagement with said first cam, said cams being related such as to move said sleeve axially to lower or permit raising of said abutment upon turning of said sleeve.

10. In a gill drawing frame having a top roller, a support for the top roller, spaced bearings slidably carried by said support and each having a semi-circular bearing recess for engaging the upper side of said top roller, an abutment movable relative to said support and positioned at a location above said top roller and extending generally parallel therewith and with the ends thereof extending in line with said bearings, a compression spring positioned between each bearing 15 and said abutment for applying a pressure on said top roller, a sleeve mounted on said support for turning movement and for axial movement, a threaded member threadedly extending through

5 said sleeve into engagement with said abutment for adjustably moving said abutment relative to said support and axially of said springs for adjusting the pressure of said springs, and inter-engaging means carried by said support and said sleeve for moving said sleeve axially to lower or permit raising of said abutment upon turning of said sleeve.
